FURNITURE PEDESTAL AND METHOD OF MANUFACTURE

Filed Dec. 27, 1924

UNITED STATES PATENT OFFICE.

CHARLES A. BROWN, OF GARDNER, MASSACHUSETTS, ASSIGNOR TO HEYWOOD WAKEFIELD COMPANY, OF BOSTON, MASSACHUSETTS, A CORPORATION OF MASSACHUSETTS.

FURNITURE PEDESTAL AND METHOD OF MANUFACTURE.

Application filed December 27, 1924. Serial No. 758,384.

Pedestals for furniture such as school chairs have commonly been made of cast iron. It is a difficult matter to so cast a pedestal that its base shall be flat to properly rest on the floor since the casting is liable to warp when cooling. If the base is not flat the pedestal is liable to be broken when being bolted to the floor. It is also liable to be broken at its upper end if the screw commonly employed to hold the chair spindle in its proper vertical position in the pedestal is set up too tightly. In order to receive the spindle also it has been the usual practice to cast integral with the pedestal a pair of lugs having tapered inner faces against which the spindle is urged by the tightening bolt. This has been done by the use of a core but if the core is not properly set in the mold these lugs are not properly related in the finished casting. As the taper is very slight, being approximately two degrees, the core must be set very accurately to produce the desired result. The cast metal pedestal is also of a quite considerable weight.

It has also been proposed to draw the pedestal from sheet metal but this has not been satisfactory because of the long neck portion or pillar of the pedestal which has been liable to break down under the drawing operation unless particularly good stock is employed in which case the expense is very considerable.

It has also been attempted to press sheet material into vertical half sections of the pedestal and then weld these sections together in pairs along vertical lines by means of an oxy-acetylene flame. In this method of welding metal is added to the sections to close the space therebetween, leaving an unsightly joint. Because of this filling of the joint also there has been considerable difficulty in producing a perfectly flat base.

According to the present method the pedestal is made by fixing together a plurality of horizontal sections, in most instances three such sections being used, the lower section comprising the base portion rounded up toward the pillar portion which may have a gradual taper. This base portion may be pressed from sheet material, preferably with a marginal stiffening flange extending downwardly, and countersunk portions for the reception of fastening screws. This piece

may be formed up accurately by the use of dies so that an accurately flat base is assured.

The next section comprises a tube or pipe which, if frusto conical, may be formed from a tube initially of the diameter of the larger end of this piece, the smaller end being swaged down to the proper size by a suitable swaging machine. The third or upper section may comprise an upper frustoconical section of a smaller sized tube or pipe, this size being that of the corresponding or smaller upper end of the second section. This may be swaged down in the same manner as the second piece and its top swaged over to form a flat end which is punched for the reception of the chair spindle. A hole is also made laterally through one side of this piece and to it is fixed, as by spot welding, a socket member with an internally threaded boss portion of the member extending out through this hole, this to receive the bolt, the inner end of which engages the spindle to fix it in proper vertical position. Also within this top section opposite to the bolt may be fixed a U-shaped frame member having a V slot cut therein to form a pair of spaced angle edges above and below the axis of the securing bolt which form two spaced bearings for the chair spindle, the bolt itself forming a third bearing on the opposite side of the spindle between the two. This construction for fixing the spindle in adjusted position forms the subject matter of a divisional application for patent Serial No. 39,427, filed June 25, 1925, for furniture pedestals. Two adjacent sections are then placed in an electric flash welding machine and welded together and the third section is welded in the same manner to these two. This method of welding forms a very thin projecting fin of metal at the joint which is easily removed by grinding and as the sections are supported on forms, the movement of which is positively controlled by the machine during the welding operation, the sections are necessarily fixed in proper relation so that the axis of the pillar is vertical when the base of the pedestal is placed on a horizontal surface.

For a more complete understanding of this invention, reference may be had to the accompanying drawings in which—

Figure 1 illustrates in elevation one form of pedestal.

Figure 2 is a longitudinal section to an enlarged scale through the three sections which are united to form the pedestal of Figure 1.

5 Figure 3 is a detail perspective of a spindle supporting element to be fixed in the upper section.

Figure 4 is a top plan of the upper section.

10 Figure 5 is a somewhat diagrammatic view showing the upper and intermediate sections being welded together.

Figure 6 is a similar view showing the upper and intermediate sections being welded to the base section.

15 Figure 7 is a top plan of another form of pedestal.

Figure 8 is an elevation of the same form.

Figure 9 is an elevation of still another form of pedestal.

20 Referring first to the form of pedestal illustrated in Figures 1 to 6, it will be noted that this pedestal is built up of three sections as best illustrated in Figure 2, a base section 1, an intermediate tapered pillar section 2, and a top section 3 also tapered and forming a continuation of the pillar section 2. The section 1 is pressed between dies to the form indicated having preferably a marginal strengthening flange 4 and countersunk openings 5 within this margin and spaced at suitable intervals around the upper face of the base for the reception of fastening screws by which the pedestal may be fixed to the floor. Somewhat within the 25 countersunk portions 5 the metal is turned upwardly on a gradual bend at 6 terminating at a central opening 7. The pillar section 2 is of a diameter at its lower end such as to mate the diameter of the margin 8 of the base section about the opening 7 and where a tapered pillar is desired the section 2 is swaged down to tapered form in a suitable swaging machine, its lower end remaining of the original diameter and its 30 upper end, as at 10, being of reduced diameter. The upper section 3 is made from a tube of a diameter equal to that of the upper end of the section 2 and if it is desired to taper it, it is swaged similar to the section 2. 35 The upper end of the section 3 may also be swaged inwardly to form a substantially flat top as at 12 which may be perforated as shown at 13 (see Figures 2 and 4) so that the spindle of the chair or other piece of furniture to be supported may slide vertically within the pedestal.

40 In order to support this spindle and to fix it at any height desired, spindle guiding and retaining means are shown as carried on the inner face of the section 3. One of these members comprises a block 15 having a boss 16 which projects through an opening 17 through the side of the upper section 3. This boss 16 is perforated and internally 45 threaded as at 18 for the reception of the

usual securing bolt 190 (Figure 1) which passes through this threaded opening so that its inner end may bear against the side face of the spindle. This block 15 may be fixed in position within the section 3 by any suitable means preferably being spot welded at two or more points thereto, one of such points being indicated at 19.

50 At the opposite side of this section is positioned a member to take the thrust of the spindle thereagainst due to the pressure exerted thereon by the securing bolt. As shown best in Figure 3 this member comprises a substantially U shaped plate 20 having its flanges 21 provided with projections 22 which may be passed through holes 23 through the wall of the upper section 3 substantially opposite to the block 15, these portions 22 then being riveted over the outer face of the section 3 to retain the member 20 in position. Extending vertically across this member 20 is a V shaped groove 25 which is formed slightly inclined, for example, two degrees from the vertical when the pedestal is positioned on a horizontal surface. The slot 25 provides a pair of spaced edge portions 26 running vertically and spaced horizontally disposed angular edges 27 against which the spindle engages, these portions 27 forming spaced bearing points on one side of the spindle while the bolt passing through the block 15 engages the opposite side of the spindle between these portions.

55 The spindle retaining means having been fixed in position in the upper section 3, this may then be welded to the intermediate section 2. The mechanism for accomplishing this welding is shown somewhat diagrammatically in Figure 5. Referring to this figure, 30 indicates the frame of the machine having mounted in ways thereon a slide 31. At one end of this slide is positioned a supporting bracket 32 of any suitable description which carries insulated therefrom a collar 33, the internal bore of which is shaped to engage the outer face of the section 3 of the pedestal. Also carried by the slide 31 by means of an internally threaded bracket bearing post 34 is a stop 35 carried at the inner end of a threaded rod 36 adjustable through the bearing post, nuts 37 thereon being employed to fix the abutment in suitable position. This collar 33 is connected to a suitable source of electric current as by a wire 38. Extending from the machine frame 30 is a bracket 40 carrying, but insulated therefrom an electro-conductive collar 41, which is adapted to be connected to the other side of the electric circuit through a wire 42, the collar 41 being formed to fit the outer face of the intermediate section 2. Also fixed to the frame 30 is an upstanding post 43 provided with an abutment portion 44 at its upper end.

Attached to the slide 31 is an arm 45 fulcrumed at 46 which arm may be rocked about its fulcrum so as to move the slide 31 by means of a rod 47 which may be actuated by any suitable source of power as for example by a compressed air cylinder shown at 50 in Figure 7. The section 2 of the pedestal is placed against the stop 44 and within the collar 41 and the section 3 is placed within the collar 33 and against the abutment 35. The slide 31 is then pressed toward the bracket 40 to bring the sections 2 and 3 together in axial alinement. Electric current is then passed through the conductors 38 and 42 through the collars 33 and 41 and the sections 3 and 2, this current being of such value as to raise the abutting edges of the sections to welding temperature whereupon the pressure exerted against the slide 31 causes the sections 2 and 3 to become welded together. After the weld has been effected the current is shut off and the slide 31 retracted so as to permit the welded sections 2 and 3 to be removed.

In the next operation the abutment 44 is provided with a platen member 51, as shown in Figure 6, against which the base section 1 may be supported in the position shown in this figure. The collar 41 is then replaced by a collar 55 of a size and contour to fit the curved portion 6 of the base section while the bracket 32 is provided with a collar 56 which fits over the lower portion of the section 2 as now welded to the section 3. The head 35 is then retracted as shown in this figure so that it bears against the upper end of the section 3 and the arm 45 is then rocked to bring the sections 2 and 3 up against the base section 1. Electric current is then caused to flow across the joint between these sections through the conducting collars 55 and 56 so as to bring these abutting edges to the welding temperature, whereupon the pressure exerted axially of the pedestal through the arm 45 causes a weld between these parts to be effected. The supporting collars in both the welding operations cause the parts to be held in proper axial position so that when the pedestal is completely welded together its pillar is vertical when its base is supported on a horizontal surface. This welding produces thin fins of metal at the joints but these are readily removed by means of a grinding operation so that a smooth well finished pedestal results.

It will be noted that such a pedestal may be of sheet material, relatively light and strong, and that there is no tendency to warp during its manufacture nor is it brittle after completion.

Of course by this method it is possible to make up pedestals of great variety of weights and sizes, certain other forms being shown in Figures 7 to 9. The pedestals of

these figures are not designed to receive a chair spindle so that the chair or other article of furniture may be adjustable in height, but in place thereof the upper section of the pedestal is designed to directly support the desired article. In the form shown in Figures 7 and 8 there is a base section 60, a pillar section 61 of substantially uniform cross section from end to end, and a top section 62 welded together in proper relation, the top section 62 being pressed up and having an inclined top face 63 which may be substantially square in plan and which may be bolted directly to the article to be supported. In Figure 9 a somewhat similar construction is shown except that the central section 65 is tapered axially similarly to the section 2 in the form shown in Figure 1, there being an upper section 66 of any desired outline in plan and which is shown as provided with an inclined upper face 67. Of course this upper face might be flat if it should be so desired.

In all of the instances shown the pedestal has been formed up of three sections welded together along substantial horizontal planes. It is evident, however, that such pedestals might be formed of any suitable number of sections, the number depending on the height of the pedestal and convenience in assembling. This method, however, insures the proper alinement of the various sections, the production of a flat base, and the accurate positioning of the upper supporting portion of the pedestal which carries the superposed article, and makes possible a light substantial construction which is admirably suited for the purpose.

Having thus described certain embodiments of this invention, it will be evident to those skilled in the art that various changes and modifications might be made therein without departing from its spirit or scope as defined by the appended claims.

I claim:

1. The method of making a pedestal which comprises forming a base section, an intermediate pillar section, and a top section fixing in said top section means for guiding and securing a spindle, and then fixing said sections together in superposed relation.

2. The method of making a pedestal which comprises forming a hollow top section having at its upper end a perforation to receive a spindle, fixing in said section beneath said upper end spindle securing and guiding means, and then fixing said section in position on the lower portion of said pedestal.

3. The method of making a pedestal which comprises pressing up a sheet metal base portion having an upwardly rounded portion terminating in a circular opening, swaging a tube section of a diameter to mate the margin of said base about said

- opening to reduce the size of its upper end, swaging an upper tube section of the same size as said reduced end to upwardly tapering form and closing off its upper end, forming a perforation through said upper end to receive a spindle, fixing spindle guiding and retaining means in said upper tube section, assembling two of said sections in axial relation, bringing their abutting edges to welding temperature and forcing them together while held in proper axial relation to effect a weld therebetween, and then welding the third section to the others in the same manner.
15. A pedestal comprising a plurality of sheet metal members arranged in superposed relation and welded together in horizontal planes, one of said sections having spindle supporting and securing means.
20. The method of making pedestals, which comprises pressing up sheet metal base portions each having an upwardly rounding portion terminating in a circular opening, swaging tubular portions to tapering for-

mation the larger ends of certain of said tubular portions being of diameters to mate the diameters of said openings, closing off the smaller ends of certain of said tapering portions and fixing spindle guiding and retaining members thereto, assembling said posts and tubular portions in axial relation with said closed ends, remote from said bases, and welding said bases and sections together.

6. The method of making a pedestal having a pillar of tapered cross section, which comprises pressing a base portion of sheet metal, swaging tubular sections to the desired taper of said pillar, closing off the upper end of the upper section and fixing spindle guiding and retaining means therein, and then welding said sections successively to said base portion while held in proper alinement.

In testimony whereof I have affixed my signature.

CHARLES A. BROWN.
